US00D826423S

(12) **United States Design Patent** (10) Patent No.: **US D826,423 S**
LiCalzi et al. (45) Date of Patent: **** Aug. 21, 2018**

(54) **INSTRUMENT MODULE**

(71) Applicant: **Siemens Healthcare Diagnostics Inc.**, Tarrytown, NY (US)

(72) Inventors: **Daniel LiCalzi**, New York, NY (US); **Mark Lloyd**, Townsend, DE (US); **Gregory Bange**, Newark, DE (US); **Richard Warwick**, Newark, DE (US)

(73) Assignee: **Siemens Healthcare Diagnostics Inc.**, Tarrytown, NY (US)

(**) Term: **15 Years**

(21) Appl. No.: **29/623,783**

(22) Filed: **Oct. 26, 2017**

Related U.S. Application Data

(62) Division of application No. 29/569,385, filed on Jun. 27, 2016, now Pat. No. Des. 804,681.

(57) **CLAIM**

The ornamental design for an instrument module, as shown and described.

DESCRIPTION

FIG. 1 is a front perspective view of an instrument module in accordance with the claimed design;

FIG. 2 is a rear perspective view of an instrument module in accordance with the claimed design;

FIG. 3 is a front elevational view of an instrument module in accordance with the claimed design;

FIG. 4 is a rear elevational view of an instrument module in accordance with the claimed design;

FIG. 5 is a left side elevational view of an instrument module in accordance with the claimed design;

FIG. 6 is a right side elevational view of an instrument module in accordance with the claimed design;

FIG. 7 is a top view of an instrument module in accordance with the claimed design; and,

FIG. 8 is a bottom view of an instrument module in accordance with the claimed design.

The broken lines shown in the figures represent portions of the instrument module that form no part of the claimed design.

1 Claim, 8 Drawing Sheets
